UNITED STATES PATENT OFFICE.

DENNIS E. LAHEY, OF GLEN JEAN, AND GEORGE R. WILLIAMS, OF THURMOND, WEST VIRGINIA.

MEANS FOR PROTECTING THE OPERATIVES OF RAILWAY ROLLING-STOCK AGAINST INJURY.

No. 909,618.

Specification of Letters Patent.

Patented Jan. 12, 1909.

Application filed June 15, 1908. Serial No. 438,620.

To all whom it may concern:

Be it known that we, DENNIS E. LAHEY and GEORGE R. WILLIAMS, citizens of the United States, residing at Glen Jean and Thurmond, respectively, in the county of Fayette and State of West Virginia, have invented certain new and useful Improvements in Means for Protecting the Operatives of Railway Rolling-Stock Against Injury, of which the following is a specification.

Our invention pertains to means for protecting the operatives of railway rolling stock against injury; and it has for its broad and general object to provide means for supporting, carrying and preventing the fall of an operative positioned over or adjacent to the meeting portions of two pieces of rolling stock in the event of such pieces pulling apart or being otherwise accidentally separated.

The invention is designed more particularly for supporting, carrying and preventing the fall of a locomotive fireman should the locomotive and its tender in any way become disconnected while the fireman is engaged in shoveling coal from the tender to the fire-box of the locomotive, and the invention in all its details will be fully understood from the following description and claims when the same are read in connection with the drawings, accompanying and forming part of this specification, in which:

Figure 1 is a side elevation, partly broken away, illustrating portions of a locomotive and tender, with our improvements properly arranged relative thereto. Fig. 2 is a horizontal section taken in the plane indicated by the line 2—8 of Fig. 1—*i. e.*, in a plane above the platform and upright guards of our improvements, and showing the locomotive and tender as separated. Fig. 3 is an inverted plan view of our improvements *per se*. Fig. 4 is an enlarged perspective view of our improvements in proper working position but detached from the locomotive and tender.

Similar letters designate corresponding parts in all of the views of the drawings, referring to which:

A is a locomotive, and B is the tender thereof, which may be and preferably are constructed and coupled in the conventional manner, though we would have it distinctly understood that they may be constructed and connected in any other manner consonant with the purpose of our invention without involving departure from the scope of the invention as defined in our appended claims.

In carrying our invention into effect we provide a platform, preferably of metal, connected with and maintained in a horizontal or substantially horizontal position from the locomotive, and adapted to normally rest in the tender and between the same and the locomotive, and we also provide the platform with guard means for preventing a fireman or other employee falling therefrom and consequently from the platform. Thus it will be manifest that a safe footing is afforded a fireman while he is engaged in shoveling coal from the tender to the locomotive and while he is passing from the locomotive cab to the tender and vice versa; and it will also be manifest that in the event of the locomotive and the tender being separated in any manner whatsoever while the fireman is performing his work or is making the passage stated, the platform and the fireman thereon will be carried with the locomotive, and the fireman will be saved from a fall between the locomotive and the tender and the injury or violent death incident thereto. This will be appreciated as an important desideratum when it is borne in mind that the operation of the steam railways of this and other countries has been attended in the past by the deaths of many firemen due to falls between locomotives and their tenders following separation of the said pieces of rolling stock while the firemen were standing over or adjacent to the meeting portions of the same.

In the present and best practical embodiment of our invention of which we are cognizant, the platform referred to comprises a rear, major section C shaped to rest between and also in front of the usual side portions of the tender and having an aperture *a* through which access may be gained to the

pin ordinarily employed to couple the locomotive and tender together, and a front and comparatively small section D, flexibly connected at E E to and adapted to swing vertically on the rear section C. The said rear section C is connected through chains F with the lower portion of the locomotive, and the said front section D is connected with the transverse sill G of the locomotive through the medium of hangers H which are hinged to the front section and are bolted, preferably in a detachable manner to the said sill G. The flexible connections E E between the rear platform section C and the front platform section D are preferably, though not necessarily, made up respectively of a member b pivoted to the section C, a member c hinged to and adapted to swing vertically on the member b and having a longitudinal slot d, and a headed bolt e extending loosely through said slot and carried by the section D. By virtue of this it will be apparent that the section D is adapted to move up and down with the locomotive without transmitting such movements to the major section C, and also, that the section D is adapted to sway or move horizontally with respect to the section C, see Fig. 4, so as to enable the platform to properly accommodate itself to the locomotive and tender when the same are taking curves—i. e., passing around a curve or passing over uneven tracks.

By virtue of the front section of the platform being detachably connected with the sill of the locomotive and connected to swing vertically on the rear platform section, it will be understood that when the front section is detached from the locomotive and swung upwardly, access may be readily gained to the parts below the front section for any purpose desired.

The guard means on the platform may be of any description suitable to its purpose, though we prefer that it comprise side sections formed by posts f and cables g, and a rear end section formed by chains h extending between the rear posts f and hooked or otherwise detachably connected to one of the same. The cables g are connected at their forward ends in a detachable or other suitable manner with the locomotive cab, with a view of preventing a lateral fall of the fireman while passing between the cab and the tender, and the purpose of detachably connecting the chains h to one of the rear posts f is to permit of said chains being lowered while the fireman is engaged in taking coal with a shovel from the tender.

Intermediate the posts f on the platform section C and the upper portion of the locomotive cab are four (more or less) cables or chains M, which have for their office to suspend the platform and maintain the same in

a horizontal or substantially horizontal position when the locomotive is separated from the tender and the weight of the fireman is imposed on said platform. In this connection it will be noted that the rear section C of the platform may and preferably does normally bear on the floor of the tender B and yet in the event of the locomotive and tender being separated as stated, the platform will draw out of the tender and will then be maintained in an approximately horizontal position by virtue of its connection with the locomotive; also, that when the separation of locomotive and tender takes place while the fireman is on the platform, the fireman will be carried by the platform and prevented from falling from the same, and he may readily pass from the platform to his seat in the locomotive cab.

With a view of holding the rear section C of the platform down on the bottom of the tender without interfering with the capacity of the platform to draw out of the tender, we provide notches a² in said section C to receive lag bolts a³ secured in the tender.

It will be gathered from the foregoing that notwithstanding the practical advantages peculiar to our improvements, the said improvements add only slightly to the cost of a locomotive and its tender; also, that the improvements are susceptible of being expeditiously and easily applied to and used in conjunction with ordinary locomotives and tenders such as at present in general use.

As hereinbefore stated, the construction we show and describe constitutes the best practical embodiment of our invention of which we are aware, but it is obvious that in the future practice of the invention, various changes in the form, construction and relative arrangement of the parts may be made within the scope of the invention as defined in the claims appended.

Having described our invention, what we claim and desire to secure by Letters Patent of the United States, is:

1. The combination of a locomotive, the tender thereof, and a platform carried by the locomotive and separable from the tender and comprising a front section hinged to and adapted to swing vertically on the locomotive, a rear section extending into the tender, and connecting devices hinged to one section to swing vertically thereon and connected with and adapted to move horizontally independently of the other section, and upright guard means at the sides of the platform and also at the end thereof remote from the locomotive.

2. The combination of a locomotive, the tender thereof, and a platform carried by the locomotive and separable from the tender and comprising a front section hinged to and adapted to swing vertically on the locomotive.

- tive, a rear section extending into the tender, and connecting devices hinged to one section to swing vertically thereon and connected with and adapted to move horizontally independently of the other section, and suspension means interposed between the upper portion of the locomotive and the platform for hanging the latter from the former.
3. The combination of a piece of railway rolling stock, a platform connected with and extending beyond the end of said piece sufficiently far to rest above an adjacent piece, and upright guard means at the sides of the platform and also at the end thereof remote from the first-named piece of rolling stock.
4. The combination of a locomotive, the tender thereof, a platform connected with and extending beyond the end of the locomotive and also extending into the tender and separable from the latter, and upright guard means at the sides of the platform and also at the end thereof remote from the locomotive.
5. The combination of a piece of railway rolling stock, a platform connected with and extending beyond the end of said piece sufficiently far to rest above an adjacent piece, suspension means interposed between the upper portion of the first-named piece of rolling stock and the platform for hanging the latter from the former, and upright guard means at the sides of the platform and also at the end thereof remote from the first-named piece of rolling stock.
6. The combination of a locomotive, the tender thereof, a platform connected with and extending beyond the end of the locomotive and also extending into the tender and separable from the latter, means interposed between the upper portion of the locomotive and the platform for hanging the latter from the former, and guard means at the sides of the platform and also at the end thereof remote from the locomotive.
7. The combination of a locomotive, the tender thereof, and a platform separable from the tender and comprising a front section hinged to and adapted to swing vertically on the locomotive, and a rear section extending into the tender and connected with the front section by means which enable it to move horizontally independently of the front section.
8. The combination of a locomotive, the tender thereof, and a platform separable from the tender and comprising a front section hinged to and adapted to swing vertically on the locomotive, a rear section extending into the tender, and connecting devices hinged to one section to swing vertically thereon and connected with and adapted to move horizontally independently of the other section.
9. The combination of a locomotive, the tender thereof, and a platform separable from the tender and comprising a front section hinged to and adapted to swing vertically on the locomotive, a rear section extending into the tender, and connecting devices hinged to one section to swing vertically thereon and connected with and adapted to move horizontally independently of the other section.
10. The combination of a locomotive, its tender, and a platform connected with and suspended from the locomotive and equipped with guard means releasable at the rear and connected at the forward end of the platform with the locomotive; the said platform normally resting in the tender and being separable therefrom.
11. The combination of a locomotive, the tender thereof, a platform connected with and extending beyond the end of the locomotive and also extending into the tender and separable from the latter, upright guard means at the sides of the locomotive and also at the end thereof remote from the locomotive, and suspension means interposed between the side guard means and the upper portion of the locomotive.
12. The combination of a locomotive, the tender thereof, a platform connected with and extending beyond the end of the locomotive and also extending into the tender and separable from the latter, upright guard means at the sides of the locomotive and also at the end thereof remote from the locomotive; said means comprising posts and chains, and suspension means interposed between the posts of the guard means and the upper portion of the locomotive.
13. The combination of a locomotive having a cab, a tender, a platform connected with and extending beyond the end of the locomotive and also extending into the tender and separable from the latter; said platform comprising sections connected together and capable of vertical and horizontal movement with respect to each other, and suspension means interposed between the upper portion of the locomotive cab and the platform section remote from the locomotive.
14. The combination of a locomotive having a cab, a tender, a platform connected with and extending beyond the end of the locomotive and also extending into the tender and inseparable from the latter; said platform comprising sections connected together and capable of vertical and horizontal movement with respect to each other, guard means at the sides of the platform and also

at the end thereof remote from the locomotive, and suspension means interposed between the upper portion of the locomotive cab and the guard means on the platform section remote from the locomotive.

15. A platform for the purpose described comprising lapped sections, a hinged support for one section, a hinged connection between the two sections, said hinged connection comprising means for permitting rela-

tive vertical and horizontal movements between the two sections.

In testimony whereof we affix our signatures in presence of two witnesses.
